MANUAL AND AUTOMATIC SWITCH TIMER

Robert L. Boyles, Framingham Center, Mass., assignor to General Electric Company, a corporation of New York

Application May 23, 1951, Serial No. 227,888

5 Claims. (Cl. 161--1)

1

My invention relates to a switch operating timer by means of which a switch may be operated automatically at a predetermined adjustable time and provided with means for opening or closing the same switch manually at any time and suspending automatic control thereof temporarily or indefinitely. The main object of my invention is to provide a single manual adjusting device, (1) for setting the time at which an automatic switch operation will occur, (2) for opening and closing the switch manually, and (3) for conditioning the timer for automatic or nonautomatic operation, and in this respect may be considered as an improvement of the timer described in United States Patent No. 2,421,986, June 10, 1947, to Bohman, and assigned to the same assignee as the present invention. My control mechanism may be used where the automatic operation occurs in response to the rotation of either a 12-hour or a 24-hour cam.

The features of my invention which are believed to be novel and patentable will be pointed out in the claims appended hereto. For a better understanding of my invention reference is made in the following description to the accompanying drawings in which Fig. 1 represents a perspective exploded view of a timer embodying my invention; Fig. 2 is a face view of the timer of Fig. 1; Fig. 3 is a side view of the setting and adjusting shaft in an intermediate axial position; Fig. 4 is a partial plan view of the mechanism of Fig. 1; Fig. 5 is a perspective view of a control actuator used in my invention; Fig. 6 shows a side view of a switch operating cam and cam follower used in my invention with the latter in the depression of the cam; Fig. 7 is like Fig. 6 but with the cam follower raised off the cam; Fig. 8 is like Fig. 6 with the cam follower resting on the raised surface of the cam; Figs. 9 and 10 show details of a modified cam and cam follower.

The timer to be described includes a synchronous motor-driven clock, the motor stator, field and gear reduction casing being designated in Fig. 1 by the numerals 1, 2, and 3, respectively. A gear 4 is driven by the motor through the reduction gearing enclosed within casing 3, and this latter gear drives through further speed reducing gears including a gear 5 to operate the minute hand shaft 6 in a clockwise direction at one revolution per hour. The hollow hour hand shaft 7 is driven through back gears 8, 9, 10, and 11 in a clockwise direction at one revolution in twelve hours. Minut and hour hands 12 and 13 are secured on their respective shafts and indicate with respect to a clock dial as shown in Fig.

2

2. The clock may be set by a front button 14 on the minute hand shaft, a slip friction clutch at 15 permitting such setting. A switch operating cam shaft 16 and a time setting dial 17 are driven through a slip friction clutch at 18 from the shaft of back gears 9 and 10. The time setting dial 17 is one a hollow shaft 19 and is driven through gears 20 and 21 at one revolution in twelve hours in a clockwise direction and hence ordinarily rotates with the hour hand 13, and a pointer 22 which is a rearward extension of the hour hand 13 indicates on dial 17 the time for which the cam shaft 16 is set for an automatic switching operation. The cam shaft 16 will ordinarily be driven at one revolution in twelve or twenty-four hours. In the present example it is driven at one revolution in twenty-four hours through gears 23 and 24 and has on it a cam 25 for actuation of the cam follower and switch operating lever 26.

The cam 25 has a depression 27 therein with nearly radial rise and fall surfaces so that the cam follower can drop therein but cannot ride radially outward. The cam follower lever is made flexible in a sidewise direction, and its cam contacting portion 28 lies at the extreme lower edge thereof and at an angle of about 45 degrees to the axis of rotation of the cam shaft and cam and hence while the cam follower cannot ride out of depression 27 in a radial direction, it may be pushed out sideways and hence does not block rotation of the cam. The cam rotates in a clockwise direction and hence the cam follower 26 will be pushed out of the depression 27 to the front as viewed in Fig. 1. This pushed-out position of the cam follower is represented in dotted lines in Fig. 4.

The cam follower lever 26 is pivoted at 29 on an axis parallel with the axis of cam shaft 16 and is provided with an extension 30 beyond the pivot. This extension 30 is made of insulating material and bears downward against a resilient switch contact member 31. Switch contact member 31 is biased upward towards a second switch contact member 32. The contacts are normally biased to a closed condition and will close when the cam follower 28 drops into the depression in the cam or is otherwise moved from a raised to such lowered position. When the cam follower rests at any point on the raised portion of cam 25 or is raised above the cam, cam follower lever extension 31 presses down on contact 31 and opens the switch contacts. A variety of switching arrangements may be used with my invention, and it is not limited to a normally closed single throw

switch which is held open when the lever 26 is in a raised position.

The switch contacts are supported by an insulating support at 33 and are provided with terminal facilities at 34 for connection in the circuit to be controlled. In Fig. 1 the parts are positioned with the switch contacts open, with the cam follower 28 resting upon a raised surface portion of cam 25 and, assuming the clock to be in operation, is about to drop into the cam depression 27 and allow the switch contact 31 to close against contact 32. Thereafter as the cam rotates, the cam follower part 28 will be pushed forward out of the depression in its lowered position as represented in dotted lines in Fig. 4, and switch contacts 31 and 32 will remain closed.

Provision is made for setting the cam shaft and dial 17 relative to clock time so as to adjust the time when the above described automatic switching operation will occur. For this purpose the rotary setting shaft 35 is provided. It is provided with a thumb piece 36 accessible from the front of the clock and with a gear 37 which when meshed with gear 24 allows the cam shaft 16 and its cam 25 and the dial 17 to be rotatively adjusted relative to clock time by reason of slippage at clutch 18. Setting shaft 35 is movable axially to mesh and demesh gears 37 and 24 for other purposes to be described. The gear 24 may have a circular scale of time graduations inscribed thereon to rotate past a window 38 in the clock dial to show the setting in the number of hours or other time units before the automatic switching operation previously described will occur. In the case of the 24-hour timer the graduations on gear 24 will be from 0 to 24 hours as represented, 0 being opposite the window when the cam 25 is in position to close switch 31-32. This is helpful in preventing mistakes in setting, particularly with respect to distinguishing between a. m. and p. m. settings in a 24-hour timer.

It will be understood that dial 17 is so rotatively related to cam shaft 16 that pointer 22 will indicate on dial 17 the clock time for which the device is set. Thus, in Fig. 2, the setting is for an automatic switch operation shortly before 3:00 o'clock, and the indication in window 38 shows that such setting is with respect to the presently indicated clock time and not twelve hours later.

As indicated previously, the switch comprising contacts 31 and 32 is to be operated manually by use of the button 36 and to accomplish this object, I provide the actuator best shown in Fig. 5 which is rotatively mounted on cam shaft 16 just to the rear of cam 25 and which is provided with a hub 39 for that purpose. This actuator has a gear sector 40 with which gear 37 is adapted to mesh when the shaft 35 is moved to the rear. In the exploded perspective view of Fig. 1 this is represented for convenience by a second gear but in the actual construction, a single gear 37 is used and the spacing relation between gear sector 40 of the actuator, gear 37 and gear 24 is more nearly as represented in Fig. 3. Hence, it is to be understood that gear 37 may be demeshed from gear 24 and meshed with gear sector 40 by moving shaft 35 to the rear, and that in an intermediate position of gear 37, indicated in Fig. 3, it is out of mesh with both. The shaft 35 has a knob on its rear end which, when the shaft is pushed to the rear to mesh gear 37 with gear sector 40, is grasped between resilient detent fingers 41, and this retains the shaft in this posi-

tion until forcibly removed by pulling the shaft forward. Also, the resilient detent imposes sufficient friction with respect to the rotation of shaft 35 to prevent rotation of shaft 35 and the actuator 5 due to gravity or vibration, although these parts are easily rotated by turning shaft 35 by the thumb piece 36. There is a hub extension 37a to the rear of gear 37 which acts as a stop against clock plate 37b to limit the travel of shaft 35 and correctly position the same when pushed to the rear, and the gear 37 itself stops against the front clock plate 37c to limit its travel when pulled out.

The actuator gear sector 40 is made sufficiently 15 resilient in a sideways direction that in case its teeth and those of gear 37 are not in alignment initially during a gear meshing operation, no harm is done. In such a case the gear sector is simply sprung to the rear slightly until shaft 35 is turned to align the gear teeth and then gear sector 40 snaps into mesh by a return sidewise movement.

The actuator is provided with two forward extending arms 42 and 48 at different radial positions. Arm 42 extends beneath cam follower 25 lever 26 and is used for the purpose of lifting cam follower part 28 of such lever away from cam 25 when the actuator is turned in a clockwise direction. Fig. 7 shows the position of the parts following such a lifting operation. Fig. 6 shows the position of the parts just following an automatic switch closing operation where cam follower part 28 has dropped into the depression 27 in cam 25. From such a position, Fig. 6, the switch may be 30 immediately opened manually by pushing in on button 36 and turning it counterclockwise. This results in the condition shown in Fig. 7.

If it is desired that the switch remain open indefinitely and subsequent automatic operation 40 be suspended until the device is reset for automatic operation, the gear 37 is left in mesh with gear sector 40 in the rotary position shown in Fig. 7. The friction on shaft 35 occasioned by the resilient detent at 41 will hold the actuator 45 in the position shown in Fig. 7 with cam follower lever 36 raised and the switch open. It will of course be understood that the operation just described for lifting the cam follower may be performed at any time and for any rotary position of cam 25, and hence, may be used not only to 50 open the switch when closed but also to prevent its closing automatically at the next automatic closing period.

If after the actuator has been positioned as 55 shown in Fig. 7, it be desired that the device be set to close the switch automatically at the next automatic operating period, the gear 37 is demeshed from gear sector 40. Friction of detent 41 is now removed from the actuator. The weight of lever 26 resting on arm 42 tends to turn the actuator counterclockwise but to prevent this, in the form of the invention shown, I prefer to provide a shallow notch at 43 in the lower edge of the cam follower lever 26 into 60 which arm 42 may be engaged to lock the lever in the raised position. Thus, when the switch has been closed automatically, it may be opened manually and immediately and it will stay open even though the actuator gear be demeshed immediately. The cam follower lever may be unlocked manually by turning the actuator counterclockwise through button 36 and the intermediate gearing, and it may be unlocked automatically by providing the cam 25 with a rise such 65 as shown at point 44 sufficient to engage and lift 70 75

the cam follower part 28 so that the notch 43 is lifted sufficiently above arm 42 for arm 42 to clear the notch 43 in rotating counterclockwise, and the actuator is released and turns by gravity or otherwise in a counterclockwise direction. This automatic unlocking action is shown in Fig. 8.

The actuator may be so counterweighted, or I may provide a light spring as shown at 46 in Fig. 1 to assure that the actuator will turn counterclockwise when thus released. In Fig. 1 the spring 46 is secured between a stationary part 47 and the actuator and produces a light bias on the actuator in a counterclockwise direction but not sufficient to turn the actuator against the friction imposed by detent 41 when gear sector 40 is meshed with gear 37.

Thus, turning the actuator to the position of Fig. 7 and leaving the shaft 35 pushed in assures that the switch will remain open, while turning the actuator to the position of Fig. 7 and pulling shaft 35 out to disengage gears 37 and 40 permits of the immediate opening of the switch following an automatic closing operation but conditions the device for an automatic switch closing operation at the next subsequent automatic switch closing time. Thus, if the device be used as an alarm clock where the switch closes an alarm circuit, the user may immediately turn off the alarm when awakened and at the same time condition the device for alarming at the next alarm period, or he may shut it off so that it will remain off permanently. In case the cam 25 rotates once in twelve hours instead of once in twenty-four hours and is used only as an alarm clock, the shaft 35 would normally be left in the pushed-in position until after the evening alarm period and then pulled out to condition the device for the morning alarm. The automatic unlocking feature is not essential to the manual uses and purposes of the actuator.

The arm 48 of the actuator is used for closing the switch manually by rotation of the actuator counterclockwise. Its outer end is offset towards the front at a wedging angle of about 45 degrees as best shown in Figs. 1, 4, and 5 and extends out over the outer periphery of the cam 25 from back to front to the right of or clockwise of the cam follower part 28 and in rotary alignment with such cam follower part when the latter is on the outer periphery of cam 25. By rotating the actuator counterclockwise beyond the rotary position shown in Fig. 8, the arm 48 wips or pushes the cam follower 28 towards the front and off the outer periphery of cam 25 so that the follower lever 26 can rotate clockwise under the pressure of spring contact 31 and allow the contacts to close. The arm 48 will thus push the cam follower off the cam in any rotary position of the latter except, of course, when the cam follower is in the depression 27 when the switch is already closed.

After closing the switch manually it will stay closed whether the actuator be kept in gear with shaft 35 or not, and hence, it is immaterial whether the button 36 be pulled out or left in the pushed-in position. Stops are provided to limit the rotation of the actuator to its operating range. Thus, the outer end of arm 48 bears against a clock plate stud 49 when the actuator is turned counterclockwise to its limit of travel as shown in Fig. 6. This same stud may also be used as a stop for the up-and-down movement of cam follower lever 26. An extension 50 on the actuator gear sector strikes against the portion of the shaft 51 as shown in Fig. 7 when the

actuator is turned clockwise to its limit of travel. The gear 37 can be meshed with gear sector 40 at any point of the range of travel of the actuator. When the actuator is demeshed and free to move, it takes the intermediate position shown in Fig. 8 with arm 48 resting very lightly against cam follower part 28 if the latter is on the upper surface of cam 25, but with insufficient force to push the part 48 off the cam. When the cam follower 28 drops into the cam notch 23, the actuator, if free to move, will swing to the position shown in Fig. 6.

The switch clock described is suitable for various uses but was designed for use in combination with a radio receiver where the switch is used to turn on and off a radio receiving set. A typical manner of use may be as follows: Assuming the user desires to have the radio awake him in the morning, the shaft 35 is pulled out to mesh gears 37 and 24 if not already meshed, and then turned until pointer 22 indicates on dial 17 the time at which the radio is to be turned on, it being assumed the clock is in operation and indicating correct time. So far as dial 17 is concerned, the setting may be for a. m. or p. m. but by glancing at the indication in window 38, the user can readily determine the proper setting. Thus, if the setting is to be for 7 a. m. and the device is set at 9 p. m., the reading in window 38 should be 10 hours rather than 22 hours. If the switch is closed at the time of the setting, the operator then pushes button 36 in as far as it will go and turns it clockwise as far as it will go. This results in the condition shown in Fig. 7. The shaft 35 is now pulled out again, and it is immaterial whether merely pulled out part way so as to demesh gears 37 and 40, or all the way to mesh gears 37 and 24. Shortly prior to 7 a. m. the cam follower will be unlocked and ride upon cam 25, and at 7 a. m., will drop into depression 27 and close the radio switch. The switch may be left closed as long as desired, or it may be opened immediately by pushing in on button 36 and turning it counterclockwise. If the switch is opened, it may be opened permanently or temporarily until the next automatic operating period by leaving the push button in or pulling it out.

If the switch is turned off, it may be closed manually and opened manually at any time and as often as desired and permanently left in either condition, or opened and set for an automatic closing action at a selected time, all time setting, automatic, and manual switching operations being controlled by the single axially movable and rotatable button 36.

I may also use the modified form of cam and cam follower represented in Figs. 9 and 10. Here the cam 25 is circular except for a shallow, substantially 90-degree cam notch cut therein at 53. The leading edge of this notch is very gradual and serves no purpose other than to lead the cam following to the short radial trailing edge of such notch and to allow the cam follower to lower itself sufficiently to engage the radial surface of such notch as the cam turns to the automatic switch closing position. The cam follower part of arm 26 in this form of the invention is a projection 54 bent to the rear from the right-hand end of the arm 26 and which normally rests upon the periphery of the cam. This cam follower projection 54 faces the radial surface step in the cam as the cam is advanced. The edge of projection 54 is cut at a wedging angle of about 45 degrees to the plane of the

cam as shown in Fig. 10. Hence, with the cam follower rotating clockwise, Fig. 9, and the cam follower 54 resting on the periphery of the cam, the radial surface or step of the cam depression 53 will move against the sloping edge of the cam follower projection 54 as the cam follower rides into the depression, and the resilient cam follower arm 26 will be pushed sideways towards the front until its cam follower projection part 54 is pushed off the periphery of the cam, or more specifically, off the notched portion thereof, whereupon the cam follower end of arm 26 drops down to switch closing position corresponding to its position shown in Fig. 6. The lever has a portion 26a extending downward at the front side of the cam which prevents backward displacement of the lever when its cam follower part springs back over the periphery of the cam.

As shown in Fig. 9, the operating positions of the parts correspond about to those shown in Fig. 8. Thus, the actuator is in an intermediate rotary position and the cam 25 is approaching an automatic switch closing, operating position where the radial notch in the cam has engaged the forward edge portion of the projection 54 and is about to start to push cam follower arm 26 towards the front. When the projection 54 has been pushed off the cam the arm 26 drops down and the switch is closed. Thus, in the form of invention shown in Figs. 9 and 10, the arm 26 drops down and the switch is closed just after the arm has been pushed sideways towards the front and off the cam, whereas in the form of the invention as described in Figs. 6, 7, and 8, the arm 26 drops down and closes the switch and then is pushed sideways towards the front.

In the form of the invention shown in Figs. 9 and 10, the holding notch 43 of Fig. 7 and the cam unlocking action of the actuator from such notch are not required because in Fig. 9 just as soon as the arm 26 is raised about the cam by the actuator immediately following an automatic switch closing operation, the arm 26 will spring back to the rear and the cam follower projection 54 will move back over the periphery of the cam in overlapping relation with respect to the radial step therein and cannot again be shoved off sideways automatically until the cam has made substantially a full revolution. As a matter of fact, after the cam follower 54 has been pushed only part way off the cam during the approach of an automatic switch operation, the lever 26 may be raised slightly by the actuator so that the follower part 54 is raised above the radial notch and the arm 26 will then spring back to the normal position, and the automatic switch operation which was about to occur will not occur until the cam has made substantially a complete revolution.

Except for the differences described, the operation of the two forms of cams and cam followers and the action of the actuator thereon are the same. Thus, in Figs. 9 and 10 the actuator may be turned manually in a clockwise direction to raise the lever 26 and open the switch if it is closed. Likewise, the actuator may be turned counterclockwise to push the cam follower lever off the cam and close the switch when the switch is open.

The camming arrangement shown in Figs. 9 and 10 may ordinarily be set with greater precision than the form shown in Figs. 6, 7, and 8, and is somewhat more simple to build, and for these reasons is to be preferred. However, either

form of cam and cam follower employs the same actuator for manual switch operation.

What I claim as new and desire to secure by Letters Patent of the United States is:

- 5 1. In a clock, a two-position switch, a cam follower lever for operating said switch between its two positions, a clock driven cam for automatically moving said cam follower lever from a first switch operating position to a second switch 10 operating position, an actuator for moving said cam follower lever in either direction between said switch operating positions, and a shaft having both rotary and axial movements for selectively manually operating said actuator and adjusting the rotary position of said cam with respect to said clock.
2. In a clock, a two-position switch, a cam follower lever for operating said switch between its two positions, a clock driven cam and cam 15 shaft adjustable with respect to clock time for automatically moving said lever in one direction between its two switch operating positions, an actuator pivoted for rotation on the same axis as said cam for moving said cam follower lever in either direction between its switch operating 20 positions, a manually rotatable shaft parallel with said cam shaft, gearing on said actuator, cam shaft and manually rotatable shaft, the latter shaft being also axially adjustable such that in 25 one axial position the gearing between said two shafts is in mesh for the purpose of setting the cam shaft, in another axial position the gearing between the actuator and manually rotatable shaft is in mesh for the purpose of manually operating 30 said switch, and in another axial position of said manually operable shaft it is demeshed from both cam shaft and actuator.
3. In a clock, a two-position switch, a cam follower lever for operating said switch, a clock driven cam and cam shaft adjustable with respect to clock time for moving said lever automatically from one switch operating position to another switch operating position at a predetermined time, an actuator pivoted for rotation on 40 said cam shaft adjacent the cam thereon for operating said lever between its two switch operating positions, a manually rotatable and axially adjustable shaft parallel with said cam shaft, a gear drive between said shafts effective only when the manually adjustable shaft is in one axial 45 position for setting the cam shaft with respect to clock time, a gear drive between the actuator and manually adjustable shaft effective only when the latter is in another axial position to operate said switch, and means for yieldingly resisting the free turning of the manually adjustable shaft only when in the last-mentioned axial 50 position.
4. In a clock, a two-position switch, a pivoted cam follower lever for operating said switch, a clock driven cam against the periphery of which the lever is biased for operating said lever, said lever having sidewise resilience such that it may be sprung sideways from a position where 55 it rides upon the periphery of said cam to a position to one side of said cam, said cam and cam follower lever having contacting surfaces designed to push the lever sideways from the periphery of the cam, and a manually rotatable actuator pivoted for rotation on the axis of rotation of the cam and closely adjacent thereto and having a range of rotation of less than a complete rotation, said actuator having an arm extending beneath the cam follower lever such that when the lever is to one side of the cam the

actuator may be turned in one direction to lift the lever to where it will spring sideways and come to rest on the periphery of the cam, and said actuator having another arm extending outwardly and laterally of the cam follower lever at a wedging angle thereto such that when the lever is resting on the periphery of the cam and the actuator is turned in the opposite direction the lever is pushed sidewise off of the cam.

5. In a clock, a two-position switch, a cam follower lever for operating said switch, a clock driven disk-shaped cam against which said cam follower lever is biased, said lever being pivoted for movement towards and away from the axis of rotation of said cam to cause operation of said switch between its two positions, said cam follower lever also having lateral resilience so as to have a normal unstressed position in alignment with the periphery of the cam and a stressed position to one side of the cam, said lever being rotatively biased to move inwardly to-

wards the axis of rotation of the cam, said cam periphery having a short radial surface facing forwardly and said cam follower lever having a laterally extending cam follower surface facing the radial surface of the cam at a wedging angle such that when such surfaces engage and the cam is advanced the lever is pushed sideways off the periphery of the cam and then moves towards the axis of rotation of the cam to operate the switch, and a manual actuator rotatively mounted on the axis of rotation of the cam for moving said cam follower away from such axis to restore it to the periphery of the cam.
